UNITED STATES PATENT OFFICE

99,033

DESIGN FOR A DISH OR SIMILAR ARTICLE

Albert Krautheim, Selb, Germany, assignor to Oneida, Limited, Oneida, N. Y., a corporation of New York

Application February 4, 1936, Serial No. 60,979

Term of patent 7 years

To all whom it may concern:

Be it known that I, Albert Krautheim, a citizen of the Republic of Czechoslovakia, residing at Selb, Bavaria, have invented a new, original, and ornamental Design for a Dish or Similar Article, of which the following is a specification, reference being had to the accompanying drawing, forming a part thereof, said drawing being a plan view of a dish showing a portion of the edge ornamentation which is continued around the dish, the essential feature of which is the ornamentation on the rim of the dish.

I claim:

The ornamental design for a dish or similar article as shown and described.

In testimony whereof I have hereunto set my hand.

ALBERT KRAUTHEIM.
